(57) **CLAIM**

The ornamental design for a cat activity toy, as shown and described.

DESCRIPTION

FIG. 1 is a first perspective view showing our new design for a cat activity toy, in a first embodiment, taken from a front angle and showing a first side of the toy.

FIG. 2 is a second perspective view of the cat activity toy of FIG. 1, also taken from a front angle but showing a second opposite side of the toy.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof.

FIG. 9 is a first perspective view showing our new design for a cat activity toy, in a second embodiment, taken from a front angle and showing a first side of the toy.

FIG. 10 is a second perspective view of the cat activity toy of FIG. 9, also taken from a front angle but showing a second opposite side of the toy.

FIG. 11 is a front view thereof.

FIG. 12 is a back view thereof.

FIG. 13 is a left side view thereof.

FIG. 14 is a right side view thereof.

FIG. 15 is a top view thereof; and,

FIG. 16 is a bottom view thereof.

The structural features shown in broken lines depict environmental subject matter and form no part of the claimed design.

1 Claim, 8 Drawing Sheets
